PASSENGER TURNSTILE

Charles R. McGehee, Culver City, and Bruce H. Osterberg, Manhattan Beach, Calif., assignors to Western Data Products, Inc., Los Angeles, Calif.

Filed Mar. 15, 1972, Ser. No. 235,107

Term of patent 14 years

Int. Cl. D25—02

U.S. Cl. D28—1 B

Fig. 1.

Fig. 2.

Fig. 4.

Fig. 3.

Fig. 5.

Fig. 6.

FIG. 1 is a front perspective view of a single passenger turnstile illustrating a first embodiment of our design;

FIG. 2 is a left side elevation of FIG. 1;

FIG. 3 is a right side elevation of FIG. 1;

FIG. 4 is a plan view of FIG. 1;

FIG. 5 is a front elevation view of FIG. 1; and

FIG. 6 is a front perspective view of a plurality of passenger turnstiles illustrating a second embodiment of our design, the undisclosed surfaces of each turnstile being the same as those shown in the other figures.

We claim:

The ornamental design for a passenger turnstile, substantially as shown.
